UNITED STATES PATENT OFFICE.

WILLIAM K. CRAWFORD, OF BOSTON, MASSACHUSETTS.

DESIGN FOR A SHELL FOR STANDPIPE-NOZZLES.

SPECIFICATION forming part of Design No. 23,524, dated July 31, 1894.

Application filed June 29, 1894. Serial No. 516,124. Term of patent 14 years.

To all whom it may concern:

Be it known that I, WILLIAM K. CRAWFORD, a citizen of the United States, residing at Boston, in the county of Suffolk and State 5 of Massachusetts, have invented and produced a new and original Design for Shells for Standpipe-Nozzles, of which the following is a specification, reference being had to the accompanying drawings, showing a part 10 thereof.

Figure 1 is a perspective view of a shell showing my design; Fig. 2 a horizontal cross section of the same taken on the dotted line $x-x$, and Fig. 3 a vertical section on the dotted line $x'-x'$ Fig. 2.

Referring to the drawings, A represents the shell provided with a conical bore B, extending laterally through it from side to side. C

is a radial opening intersecting said bore and D a peripheral opening also communicating 20 with or intersecting said bore as shown.

The leading feature of my design is a laterally extended enlargement E, leading from the radial opening C concentrically around the bore B and in open communication there- 25 with as shown.

I claim—

The design for a shell for stand pipe nozzles herein shown and described.

In testimony whereof I have signed my 30 name to this specification in the presence of two subscribing witnesses.

WILLIAM K. CRAWFORD.

Witnesses:

GEO. W. GREGORY,
EMMA J. BENNETT.
